UNITED STATES PATENT OFFICE.

ERNEST A. F. SCOTT, OF PASADENA, CALIFORNIA.

DESIGN FOR AN INCENSE-BURNER.

53,226.

Specification for Design.

Patented Apr. 22, 1919.

Application filed January 14, 1919. Serial No. 271,150. Term of patent 3½ years.

To all whom it may concern:

Be it known that I, ERNEST A. F. SCOTT, a citizen of the United States, residing at Pasadena, in the county of Los Angeles and State of California, have invented a new, original, and ornamental Design for Incense-Burners, of which the following is a specification, reference being had to the accompanying drawings, forming a part thereof.

Figure 1 is a perspective view taken from the front, and Fig. 2 is a perspective view taken from the reversed side of Fig. 1.

I claim:

The ornamental design for an incense burner, as shown.

ERNEST A. F. SCOTT.
